Primary Examiner — Bao-Yen T Nguyen

Assistant Examiner — Amanda J Berlinski

(57) **CLAIM**

The ornamental design for an ear cleaner as shown and described.

DESCRIPTION

FIG. 1.1 : Front

FIG. 1.2 : Back

FIG. 1.3 : Top

FIG. 1.4 : Bottom

FIG. 1.5 : Left

FIG. 1.6 : Perspective

FIG. 1.7 : Perspective

The right and left views are symmetrical, so the right view is omitted.

The broken lines and faded sections within the broken lines depict portions of the ear cleaner that form no part of the claimed design.
